UNITED STATES PATENT OFFICE.

HERBERT W. JOHNSON, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed May 12, 1924. Serial No. 712,528.

The present invention relates to mechanical pencils, and particularly of the type having lead magazines from which leads may be supplied to succeed the used lead in the pencils.

Among the objects of the invention is to provide means for feeding or supplying leads successively from the magazine to the tip of the pencil to provide a mechanical pencil wherein the magazine for the extra leads is located at the rear end of the pencil so that the magazine can be filled from the rear of the pencil, and wherein the pencil is provided with mechanism for automatically and positively feeding a succession of leads in predetermined order from the magazine to and through the pencil tip; to provide means, which when operated manually will automatically supply the lead from the magazine to succeed the lead that has previously been fully fed or used; to provide means whereby the succeeding lead from the magazine may be fed into loading or charging position at the same time of the feeding of the lead being used at the tip of the pencil; to provide feeding means or mechanism with a movable feeding element which when it moves in one direction will feed the lead to be used as well as a magazine lead to follow the first mentioned lead and when moved in a reversed or retracted direction will operate to automatically move the magazine lead into feeding position behind of or successive to the lead previously fully fed; and to provide such other objects, advantages and capabilities as will later more fully appear and are inherently possessed by the invention.

Referring to the drawings illustrating a preferred embodiment of the invention, Fig. 1 is a longitudinal sectional view of a pencil constructed in accordance with the invention; Fig. 2 is a similar view taken transversely to that shown in Fig. 1; Fig. 3 is a view similar to Fig. 2 with parts further sectioned; Fig. 4 is a view in perspective showing parts of the pencil partly in section and partly in fragments; Fig. 5 is a fragmentary longitudinal sectional view showing the feed rod at its forward or lower end of travel and with a new or magazine lead ready to be loaded into the feed channel or tube of the device; Fig. 6 is a transverse sectional view taken on line 6—6 of Fig. 1; Fig. 7 is a transverse sectional view taken

on line 7—7 of Fig. 1; Fig. 8 is a transverse sectional view taken on line 8—8 of Fig. 1; Fig. 9 is a transverse sectional view taken on line 9—9 of Fig. 1; Fig. 10 is a transverse sectional view taken on line 10—10 of Fig. 5; Fig. 11 is a view, partly in fragment, similar to Fig. 10 but showing parts when the feed slots have moved through substantially 90 degrees and when a new lead has been inserted in place, dotted lines being used to indicate the relative positions of the upper parts; Fig. 12 is a view in perspective of the magazine shell; Fig. 13 is a perspective view, partly in section, of the charging tube; Fig. 14 is a view in perspective, with parts separated, of the guide sleeve and control member; and, Fig. 15 is a view in perspective of the feed screw, feed rod and feed tube.

Referring now more in detail to the drawings, the particular embodiment chosen to illustrate the invention is shown as comprising a barrel 1 having, at its forward end, a tapered portion 2, and at its rear end, a threaded portion 3 to which may be threaded a coupling piece 4 suitably secured to a belled portion 5 at the rear end of a magazine shell 6 included within the barrel 1. At the forward end of the barrel is connected a rifled tip 7 which has a threaded shank 8 to which is connected a plug 9 having tapered exterior to fit with the tapered portion 2 of the barrel. The plug 9 is of such a length as to provide a socket 10 in which rotatably fits a bearing portion 11 of a cup shaped member 12 containing the lower ends of a charging tube 13 and a feed tube 14 of the feeding mechanism as clearly shown in Figs. 1, 2, 3 and 5 of the drawings.

The charging tube is shown in detail in Fig. 13 and comprises a tubular member having a longitudinal feed slot 15 extending nearly the whole length thereof and has connected substantially midway of the tube or intermediate the ends of the tube a cross-head 16 of substantially circular form but having a radial slot 17 in alignment with the slot 15 and also having a peripheral rib 18 for aiding in locating the mechanism substantially centrally or concentric in the barrel 1. At one side of the rib 18 is formed a shoulder 19 for the receiving and engaging of the lower end 20 of the magazine shell 6. At the other side of the rib 18 or below the same as shown in Fig. 13, is a shoulder

21 upon which is fitted an annular body portion 22 of a spring 23 extending toward the point or tip of the pencil and arranged substantially parallel to the slot 15 and opposite the same. This spring has preferably 5 guide ears 24 and 25 extending laterally from the spring 23 and capable of moving into and out of engagement with slots 26 and 27 formed in the side of the tube and 10 at the sides of the slot 15. It may thus be seen that the spring 23 may lie in the slot 15 to the extent permitted by the entry of the ears 24 and 25 into the slots 26 and 27. See the details shown in Fig. 4 of the drawings. The spring 23 is connected to the band portion 22 by a bent portion 28 so as to leave a space between the slot 15 and the bent portion 28 for the passage of a magazine lead as will later more fully appear. This bent 15 portion 28 is tapered or bent to form a guiding surface 29 for the end of the lead, and is located opposite the slot 15 as well as in alinement with the slot 17, the latter being a passage through which the magazine lead 20 will pass when being fed from the magazine to a position to be loaded into the feed tube 14.

Within the charging tube 13 is a feed tube 14, a feed screw 30 and a feed rod 31 shown 25 in details in Fig. 15 of the drawings. The feed tube 14 is provided with a channel or slot 32 extending the length thereof to provide a slot or opening at one side of the tube 14. The lower end portions of the charging 30 tube 13 and the feeding tube 14 extend into the cupped portion 12 and are rotatable in said cupped portion, or, if desired, the cupped portion 12 may be secured to the lower end 35 of the charging tube 13 and have its bearing portion 11 rotatable in the socketed portion 10 of the plug 9. The channel 32 is 40 designed for guiding and holding a lead 33 being fed to the tip 7 of the pencil. In Fig. 1 is shown the position of the lead following 45 a previously fed portion 34 extending through the axial bore or passage of the tip 7. The tube 14 is capable of angular movement or rotation within the charging tube 13. Within the channel 32 is longitudinally 50 movable the feed rod 31, the lower end of which is provided with a laterally bent end portion 35 which acts both as the feeding end for moving the lead longitudinally in the channel and also as a means for rotating 55 the tube 14 in the charging tube 13 when it is desired to bring the slot or the channel 32 in registry or opposite the slot 15 of the charging tube as shown in Fig. 11 of the drawings. At the other end of the rod 31, 60 which extends within the axial bore or passage of the screw 30 is provided a bent portion or crook 36 having a lead engaging or loading end 37 extending toward the forward end of the pencil. The screw 30 is 65 provided with an open helical slot 38 in

which operates the crook 36 for longitudinal movement of the rod 31 forwardly or rearwardly upon the rotation of the screw 30 in one direction or the other. The screw 30 is rotatably supported in the upper part 39 of the charging tube 13 with the lower end 70 of the screw 30 normally bearing against the upper end of the feed tube 14 and the upper end of the screw 30 being secured in any suitable manner to a finger piece 40 by 75 which the screw 30 and the finger piece 40 may be rotated by the fingers of the operator. Surrounding the upper part 39 of the charging tube 13 is provided a guide sleeve 41 having its lower end portion bearing 80 against the top surface of the member 16 and its upper end portion provided with a tongue 42 which extends through a slot 43 formed in a flanged portion 44 at the upper end of the charging tube 13, all as is clearly 85 shown in Fig. 13 of the drawings. The guide sleeve 41 is made of sheet metal and so shaped to provide an open channel or slot 45 for the passage of the crook 36 and feed or loading end 37 of the rod 31 in one 90 direction of movement thereof, and has a return channel 46 for the return of the crook 36 and end portion 37 when moving in another direction, that is, when the rod 31 is being retracted or returned to starting position for feeding another lead. The upper end of the guide sleeve 41 bears against the flange 44 and the sleeve is capable of rotation between said flange 44 and the cross-head 16 to the extent hereinafter more fully 95 explained.

The magazine shell 6 surrounds the guide sleeve 41 and this guide sleeve fits loosely and rotatably within the shell 6, and this shell is screwed into and held stationary in 100 the barrel 1. It is provided with a longitudinal slot 47 through which leads may be loaded into the magazine, the space between the shell 6 and the sleeve 41 constituting the magazine space in which the leads are 105 located. At one side of the slot 47 is an inwardly bent flange 48 which cooperates with a shoulder 49 forming a side portion of the channel 46 when the sleeve 41 is rotated in one direction as hereinafter more fully explained. See Fig. 7 of the drawings.

Extending upwardly from the flange 44 is a chamber 50 internally screw threaded for engagement to a threaded plug 51 having a flange 52 engaging the rear end of the barrel 1 and the coupling member 4. The finger piece 40 has a hub portion 53 rotatably mounted in the plug 51 and provided with a groove for receiving a thrust collar 54. It will be apparent that the finger piece 40 is 120 rotatable in the plug 51 but cannot slide longitudinally thereof by reason of the collar 54 locking it in place in the plug.

Within the chamber 50 is located a control member 55 having a longitudinally cut 125

sector shaped slot 56 for providing contact faces or shoulders 57 and 58 against which the bent portion 36 of the rod 31 may contact before and after reversal of the movement of the rod 31. The member 55 is formed with a flange 59 having an arc shaped slot 60 for providing at the ends of the slot, shoulders 61 and 62 for engagement with one side or edge or the other 10 of the tongue 42 formed on the upper end of the guide sleeve 41. See Fig. 14 of the drawings.

The finger piece 40 may be socketed for the reception of an eraser 63 as shown in Figs. 15 1, 2 and 3 of the drawings.

The leads in the magazine may be any number from one to twelve. The sleeve 41 together with the cooperating parts such as the screw portion 30 and the shell 6 are designed and arranged to position the leading lead 65 to be engaged by the end 37 of the feeding rod 31 when moved downwardly or forwardly in the pencil. For this purpose the channel portion of the sleeve 41 is formed 25 with a flange 66 capable of engaging with the leading lead 65 when the sleeve 41 is rotated in clockwise direction as viewed in Fig. 7 of the drawings. This rotation may be effected by the frictional engagement between the screw 30 which will frictionally turn the sleeve portion 39 which in turn may frictionally turn the tubular portion of the sleeve 41 or positively by means of the edge 67 engaging with the edge 68 of the 35 flange 66, as shown in Fig. 7 of the drawings. The leading lead 65 will be held in position by its contact with a succeeding lead in series until the last lead 69 engages with the flange 48 of the shell 6. If we assume 40 that there are less leads than the full quota of the magazine, as for example if there be but seven leads instead of twelve leads, the leading lead will then be that designated by reference character 70 and the space between the lead 70 and the flange 66 will remain empty of lead. In such case the initial turning of the screw 30 will effect an engagement of the edge 67 against the flange 68 and the three members, namely the screw 45 30, the tube portion 39 and the sleeve 41, will turn clockwise in unison until the flange or shoulder portion 66 engages against the lead 70 when rotation of the sleeve 41 and the tube portion 39 will cease but the screw 50 30 may continue to rotate as the friction between it and the tube 39 is not such as to prevent it. It will thus be apparent that continued rotation of the screw 30 will cause a longitudinal feed of the rod 31 downwardly, so that the end 37 will move the magazine lead 70 downwardly and longitudinally. It will, of course, be understood that when the three members are moving as a unit until the flange 66 engages with the lead 65 70, the crook portion of the rod 31 also moves

as an element of the unit when it is moved from the dotted line position thereof designated by the reference character 71 in Fig. 7 of the drawings until it is brought to a stop opposite the upper end of the lead 70. 70 If however, there is a full quota of leads in the magazine and as shown in Fig. 7 of the drawings, the leading lead 65 will be the lead engaged. In this case there will be practically no rotation, or very little rotation, until the flange 66 engages with the lead 65, and, the hook 37, when caused to move longitudinally by the continued rotation of the screw 30, will then engage with the upper end of the lead 65 to move it 80 downwardly and longitudinally. From the above it will be apparent that for each lead of the magazine the amount of movement of the parts until the hook is brought into position opposite the upper end of the leading lead will be greater for each lead until the last lead 69 is reached when the feeding of that lead will empty the magazine.

Assuming the parts to be in the relation shown in Figs. 1, 2, and 3 of the drawings, when the rod 31 is ready to be fed downwardly to feed a lead 33 forwardly to the tip 7, the operation is effected by a clockwise rotation of the finger piece 40 which in turn rotates the screw with likewise rotation to cause the rod 31 to be moved longitudinally forwardly. The lower end of the rod will engage with the rear end of the lead 33 and move the same longitudinally 95 toward the tip 7. At the same time the end 37 will engage one of the leads in the magazine, such as the lead 65 if it be the leading lead or the lead 70 if it be the leading lead of seven in the magazine, to feed it longitudinally forwardly so that this lead will move along the feeding slot 15 which at that time will be opposite the slot 45 of the sleeve 41, and through the slot 17 until the lower end of the lead engages with the tapered or slanted portion 29 of the spring 23 when the spring will then be forced outwardly and the lead brought into the position shown in Fig. 5 of the drawings, the spring 23 acting to hold the lead in place against the outer surface of the feeding tube 14 as shown in Fig. 10 of the drawings. When the lead 33 is in fully fed position and the lead 65 or 70 in loaded position as shown in Fig. 5 of the drawings, the crook 36 will come to a stop by engagement with the upper end of the feeding tube 14 when further longitudinal movement of the rod 31 is prevented. The finger piece is then rotated in an opposite direction or counter clockwise to retract the rod 31. Immediately upon the counter clockwise rotation of the screw 30 its frictional engagement with the tube portion 39 will cause the latter to turn with the screw and cause the opposite edge 72 thereof to move to and contact with the edge 100 110 115 120 125 130

68 of the flange 66 so that the charging tube 13 and the sleeve 41 will be carried with the screw as a unit until the shoulder 49 of the sleeve 41 contacts with the flange 48 when 5 the sleeve 41 will come to a stop together with the tube 13.

It will, therefore, be seen that as the reverse motion of the screw 30 started it first turns the hook or crook portion 36 of the 10 rod with it, together with the tube 13 and the tube 14 until the edge 72 engages with the flange edge 68 thus permitting the hook or crook portion 36 of the rod to pass from the lower end of the slot 45 to the 15 lower end of the channel 46, it being noted that the crook 36 was beneath the lower end of these two members as clearly shown in Fig. 5 of the drawings. In going from channel 45 to 46, the crook 36 does not 20 swing, but part 41 changes position so that the flange edge or lug 68 swings from the edge 67 on slot 15 to the opposite side of the slot when the finger piece 40 is rotated in counter-clockwise direction. This angular 25 motion is limited by the slot 15 to substantially 30°. When the members have come to a stop by reason of the engagement of the shoulder 49 against the flange 48 further 30 turning of the screw in counter-clockwise direction will cause the rod 31 to move rear- 35 wardly or be retracted and, from the above, it will be apparent that the crook 36 will move upwardly through the channel 46 and not interfere with any of the leads in the magazine. At this time the leads in the 40 magazine may be in a more or less loose condition. It is only material that they be packed when the loading is made from the magazine.

40 Now as the lower end 37 of the crook leaves the channel 46 further turning of the screw will have a tendency to turn the crook toward the face or shoulder 58 of the control member 55, see Fig. 6. Such turning will 45 occur by reason of the crook being carried with the screw and the control member will also turn a given distance until the shoulder 62 is brought into contact with the right hand side of the tongue 42. This permits a 50 turning movement of the rod 31 together with the bent end 35 and the feed tube 14 to substantially 90 degrees from the position shown in Fig. 10 of the drawings to the position shown in Fig. 11 of the drawings, 55 so that the slot 32 may be made to register with the slot 15 at which time the spring 23 will act automatically to load the lead 65 into the channel 32 of the feeding tube, the spring 23 then assuming the position it previously had as shown in Fig. 4 of the drawings. It will be apparent from the above 60 that the loading of the magazine lead 65 into the channel 32 in successive or following position to the fully fed lead therein occurs only at the fully retracted position of

the rod 31, since it is necessary that the lower end of the rod be cleared from the channel 32 before the magazine lead 65 be loaded therein.

The crook of the rod 31 will now have 70 reached the upper end of the helical slot of the screw as clearly shown in Fig. 4 of the drawing. It is now necessary to reversely rotate the screw, as by a clockwise rotation, whereby the crook 36 together with the 75 screw is carried toward the shoulder 57 of the control member 55 thus turning the latter until the shoulder 61 engages with the tongue 42. The turning of the crook 36 and rod 31 causes the end 35 of the rod to 80 rotate tube 14 to bring the slots 32 and 15 out of registry, or to the position shown in Figs. 8 and 9, of the drawings. At this instant the sleeve 39 by reason of the frictional engagement of it with the screw 30 will 85 cause end 67 to engage end 68 and hence cause a turning of the sleeve 41 until the sleeve 41 comes into engagement with the leading lead in the magazine. If the leads in the magazine are in loose condition they 90 will be forced into a series until the lead 69 engages with the flange 48 and then the leading lead will bring the rotation of the sleeve 41 to a stop. It will be noted that when the screw has been turned with the 95 crook 36, the crook 36 will be moved from the position opposite the upper end of the channel 46 to the upper end of the channel 45, that is, when the crook has engaged with the face 57 of the member 55 at which time 100 the crook is opposite the upper end of the channel 45 and ready to enter said channel to engage with the leading lead in the magazine to be fed as before. Continued rotation of the screw will effect the feeding of the lead 105 loaded into the feeding tube and also a feeding of another lead from the magazine under the spring 23 as described at the beginning of the operation hereinbefore.

This operation may continue until the 110 magazine is exhausted. When it is desired to load the magazine, the coupling member 4 is unscrewed from the threaded portion of the barrel 1 and the magazine shell together with the propelling mechanism including 115 the members 11 and 12 and the cross-head 16 are removed as a unit. New leads may then be dropped into the slots 47 of the shell until the magazine space is filled with leads. The mechanism may then be replaced in the 120 barrel by simply screw-threading the coupling member 4 upon the threaded portion 3 of the barrel. The assembly is thus very simple and easily carried out.

While I have described and upon the 125 drawings shown a particular embodiment of the invention, it is to be understood that the invention is not limited to the particular details, arrangement of parts and constructions shown and described, but that other 130

details, arrangements of parts and constructions are comprehended by the invention without departing from the spirit thereof.

Having thus described my invention, I 5 claim:

1. A mechanical pencil having a barrel provided with a tip and a magazine for non-aligned extra leads, and longitudinally movable means for simultaneously feeding 10 a lead into writing position and an extra lead into position to be moved to follow the first mentioned lead after it has been fed.
2. In a mechanical pencil a barrel having a tip and a magazine for non-aligned extra 15 leads, means for simultaneously feeding a lead to project through said tip and an extra lead into position to be moved to follow the first mentioned lead after it has been fed.
3. In a mechanical pencil a barrel having 20 a tip and a magazine for non-aligned extra leads, means for propelling a lead into writing position through said tip, and means operated by said first mentioned means to move an extra lead longitudinally in said 25 barrel to follow the first mentioned lead when fed.
4. In a mechanical pencil a barrel having a tip and a magazine for extra leads, a lead guiding tube, and means for simultaneously 30 propelling a lead through said tube and for longitudinally moving an extra lead which is outside of said tube.
5. In a mechanical pencil having a barrel, a tip and a magazine for leads, feeding 35 mechanism comprising means for guiding a lead to said tip during feeding operation, a movable feeding element for feeding said lead in said guiding means and having a loading part for moving a lead from said magazine to a position for loading into the guiding means, and means for moving said second mentioned lead into said guiding means successive to said first mentioned lead when in fully fed position.
- 45 6. In a mechanical pencil having a barrel, a tip and a magazine for leads, feeding mechanism comprising a lead guide provided with a lateral opening, means for feeding a lead in said guide to said tip and for 50 feeding a lead from said magazine to a position opposite said lateral opening, and means for moving said second mentioned lead through said lateral opening into said lead guide when said first mentioned lead is fully fed.
- 55 7. In a mechanical pencil having a barrel, a tip and a magazine for leads, feeding mechanism comprising a lead guide provided with a lateral opening, means for feeding a lead in said guide to said tip and for 60 feeding a lead from said magazine to a position opposite said lateral opening, means normally closing said lateral opening, means actuated by said feeding means for opening

said closing means when said first mentioned lead has reached fully fed position, and means for moving said second mentioned lead into said guide to follow said first mentioned lead.

8. In a mechanical pencil having a barrel, a tip and a magazine for leads, feeding mechanism comprising a lead guide provided with a lateral opening, means for feeding a lead from said magazine to a position opposite said lateral opening, means normally closing said lateral opening, means actuated by said feeding means for opening said closing means when said first mentioned lead has reached fully fed position, and a resilient means for automatically moving 75 said second mentioned lead into said guide behind the first mentioned lead when said closing means is opened and when said first mentioned lead is in fully fed position.

9. In a mechanical pencil having a barrel, a tip and a magazine for leads, feeding mechanism comprising a feeding member having a plurality of lead engaging portions, one of said portions acting to feed a lead to said tip and another of said portions for feeding a lead from said magazine to a position to follow the first mentioned lead when in fully fed position.

10. In a mechanical pencil having a barrel, a tip and a magazine for leads, feeding mechanism comprising a feed guide for guiding leads being fed to the tip, a movable feed rod having one end thereof arranged to engage said lead to feed the same and having the other end thereof shaped to engage a lead in the magazine to move said magazine lead therefrom to a position to be loaded into said guide, and means for moving said magazine lead into said guide when the first lead has been fed into fully fed position.

11. In a mechanical pencil having a barrel, a tip and a magazine for leads, feeding mechanism comprising a feed rod, means for reciprocating said rod, said rod having means for feeding a lead to said tip and to feed a lead from said magazine to a position to follow said first mentioned lead when moved into fully fed position.

12. In a mechanical pencil having a barrel, a tip and a magazine for leads, feeding mechanism comprising a feed rod, means for reciprocating said rod, said rod having a crook at one end thereof for engaging a lead in said magazine and moving it from the magazine when the rod is feeding a lead to the tip whereby the magazine lead may succeed the lead fed to the tip.

13. In a mechanical pencil having a barrel, a tip and a magazine for leads, means for guiding a lead to said tip, means for propelling said lead in said guiding means to said tip, said guiding means having a load-

- ing slot, means for normally closing said slot, said propelling means cooperating with said closing means for opening said slot when said propelling means has been retracted, and means for moving a magazine lead through said slot into said guiding means behind said first mentioned lead. 5
14. In a mechanical pencil having a barrel, a tip and a magazine for leads, means for guiding a lead to said tip, a reciprocable means for propelling said lead in said guiding means to said tip when said reciprocable means is moved in one direction, said guiding means having a loading slot, means for normally closing said slot, said propelling means having means for moving a lead from said magazine to a position opposite said slot and closing means, and means actuated by said propelling means at the end of its 15 reverse reciprocation to open said closing means to permit said second mentioned lead to enter through said slot into said guiding means in successive position to the first mentioned lead when in fully fed position. 20
15. In a mechanical pencil having a barrel, a tip and a magazine for leads, means for guiding a lead to said tip, a reciprocable means for propelling said lead in said guiding means to said tip when said reciprocable means is moved in one direction, said guiding means having a loading slot, means for normally closing said slot, said propelling means having means for moving a lead from said magazine to a position opposite said slot and closing means, means actuated by said propelling means at the end of its 25 reverse reciprocation to open said closing means, and means for automatically moving said second mentioned lead through said slot 30 into said guiding means in position to follow the first mentioned lead when in fully fed position. 35
16. In a mechanical pencil having a barrel, a tip and a magazine for leads, feeding mechanism for the leads comprising a slotted feeding tube, a slotted charging tube surrounding said feeding tube, said tubes being relatively rotatable to permit said slots to come into registry, said slots being normally 40 out of registry whereby the charging tube normally closes the slot of the feeding tube, means for holding a magazine lead opposite the slot of the charging tube and capable of moving said lead into said feeding tube 45 when said slots are in registry, and means for moving said tubes for registering of said slots. 50
17. In a mechanical pencil having a barrel, a tip and a magazine for leads, feeding mechanism for the leads comprising a slotted feeding tube, a slotted charging tube surrounding said feeding tube, said tubes being relatively rotatable to permit said slots to come into registry, said slots being 55 normally out of registry whereby the charging tube normally closes the slot of the feeding tube, means for holding a magazine lead opposite the slot of the charging tube and capable of moving said lead into said feeding tube when said slots are in registry, lead 60 propelling means movable in one direction for feeding a lead in said feeding tube to said tip and a lead from said magazine to position opposite the slot in said charging tube, and movable in an opposite direction 65 to move the tubes for registry of the slots whereby the magazine lead may enter the feeding tube in following position to the lead previously fed in the feeding tube. 70
18. In a mechanical pencil having a barrel, a tip and a magazine for leads, feeding mechanism including a reciprocable feeding rod movable in one direction for feeding a lead to said tip and a lead from said magazine to follow the first mentioned lead, 75 means for rotatably supporting said rod, means for guiding the first mentioned lead to the tip, means normally closing said guiding means and operated to open upon the rotation of said rod in one direction of 80 rotation and to close said guiding means when rotated in another direction, and means for moving the magazine lead into the guiding means when the closing means is in open position. 85
19. In a mechanical pencil, a barrel having a tip and a magazine for extra leads, and a lead propeller formed to simultaneously and longitudinally propel two non-aligning leads in said barrel. 90
20. In a mechanical pencil, a barrel having a tip and an extra lead magazine, a lead guide tube, a propeller for moving a lead through said tube into writing position, and means associated with said propeller for moving an extra lead longitudinally from said magazine. 100
21. A mechanical pencil having a barrel provided with a tip and provided with a magazine at its rear end adapted to store unaligned extra leads, said pencil having a shiftable exterior part and means within the barrel actuated by movement of said part for positively feeding the leads in succession from the magazine to and through the tip. 105
22. A mechanical pencil having a barrel formed with a tip and provided with a magazine at its rear end for holding extra unaligned leads, and propeller means for automatically feeding the leads in predetermined sequence from the magazine to and through the tip. 110
23. A mechanical pencil having a barrel provided with a tip at its front end and a magazine in its opposite end adapted to store a row of unaligned extra leads, said pencil having manually operable means for 115 120 125

positively feeding the foremost leads of the row in succession from the magazine to and through said tip.

24. A mechanical pencil having a barrel 5 provided with a tip at its front end and a magazine at its opposite end adapted to store extra leads, said pencil having means operable positively to feed said leads in succession from the magazine substantially 10 transversely of said barrel and forwardly to and through said tip.

25. A mechanical pencil having a barrel provided with means forming a longitudinal and axial lead passage terminating in a tip, 15 and having a magazine adapted to store extra leads, means for feeding a lead through said tip and supplemental feeding means adapted to be moved into any one of a plurality of positions extending about said lead 20 passage and adapted to be moved parallel to said passage to feed from the magazine a subsequent lead to said tip passage.

26. A mechanical pencil having a barrel provided with a tip and a magazine for holding a row of unaligned leads, a feed 25 member, means to shift said member into position opposite an end of the foremost lead of the row and to shift said member in the direction of said end to move the lead 30 forwardly.

27. A mechanical pencil having a barrel provided with a tip and a magazine for a row of leads, lead feeding means, mechanism adapted to move the feeding means a predetermined 35 distance to a position opposite the end of a lead in the magazine, and devices controlled by the number of leads in the magazine for determining such distance and means for feeding said lead feeding means 40 toward the end of the lead to propel said lead.

28. A mechanical pencil having a barrel provided with a tip and a magazine adapted 45 to hold a row of leads, a feed member, means to shift said member transversely of the axes of said leads into position opposite an end of the foremost lead of the row and to shift said member in the direction of the end of the lead to propel it forwardly.

29. A mechanical pencil having a barrel provided with a tip and a magazine adapted 50 to hold a plurality of leads, a feed member, means to shift said member transversely of the axes of said leads to position it opposite the end of a lead and to shift said member in the direction of the end of said lead to propel it.

30. A mechanical pencil having a barrel provided with a tip and a magazine forming 60 a lead space concentrically about the axis of the pencil, a feed member, means to shift said member across said space into any desired position and opposite the end of a lead in said chamber and means to feed said mem-

ber toward the lead and to propel the lead 65 forwardly toward the tip.

31. A mechanical pencil having a barrel formed with a tip and an arcuately shaped magazine disposed concentrically about the axis of the pencil and adapted to receive an 70 arcuate row of leads, a lead feeding member and means to selectively move said member varying distances in an arcuate path into position immediately opposite the end of the foremost lead of the row and to cause said 75 member to push said lead forwardly toward the tip.

32. A mechanical pencil having a barrel formed with an axial passage terminating in a tip, a feed rod shiftable through said passage, a magazine for extra leads concentrically disposed about the axis of said passage, lead feeding means carried by said feed rod and means to move said lead feeding means transversely of said magazine into position opposite the end of a lead, and mechanism to move said lead feeding means substantially transversely to its first path of movement to feed said lead forwardly.

33. A mechanical pencil having a barrel 90 formed with a tip, a slotted charging tube extending axially of the barrel and communicating with the tip, a slotted feed tube and hollow feed screw mounted within the charging tube, a feed rod within the screw 95 and feed tube, said rod having a lateral crook at its upper end, a guide sleeve surrounding the upper portion of said charging tube, said sleeve having a slot and a channel, a slotted shell surrounding said guide sleeve 100 and spaced therefrom to provide a lead magazine, and control devices for rotating said guide sleeve, charging tube, feed screw and feed rod together or to cause their relative rotation to propel a lead from the magazine 105 to the feed tube.

34. A mechanical pencil having a barrel provided with a tip and a magazine adapted 110 to hold a row of unaligned leads, a feed member shiftable into position opposite the end of any one of said leads when occupying the foremost position in the row in the magazine and means for moving said member in the direction of the end of the lead to propel it.

35. A mechanical pencil having a barrel and a tip through which the leads are fed, a magazine for storing leads within the barrel, a feed rod for advancing leads through the tip, said rod having a supplemental lead feeding portion for advancing a lead 120 through the magazine, said portion being rotatable about the axis of the rod.

36. A pencil having a barrel provided 125 with a magazine for extra leads, and having a tip, a rod in said barrel having two lead contacting portions and means for shifting said rod for simultaneously feeding a lead

through the tip and through the magazine.

37. A pencil having a barrel provided with a tip and a magazine for extra leads, a rotatable feed screw, a rod and means for causing said rod to rotate with said screw or to move longitudinally thereof whereby to feed leads from the magazine toward the tip.

38. A mechanical pencil having a barrel provided with tip and a magazine for extra leads, a feed screw, a lead feed rod actuated by said screw and having a crook, a slotted charging tube surrounding said screw, and a slotted guide-sleeve surrounding said tube, said screw tube and sleeve having frictional driving faces and having portions to engage said crook for causing said feed rod to rotate with said screw or to travel longitudinally thereof to feed a lead from said magazine to said tip.

39. A mechanical pencil having a barrel provided with a tip, a partition extending across said barrel intermediate its ends and forming a lead magazine on that side of the partition removed from the tip, a feed rod adapted to move axially through said partition to feed leads to and through the tip, said partition having an eccentric feed slot therethrough, and means for feeding a succession of leads from the magazine through said eccentric slot.

40. A mechanical pencil having a barrel formed with a tip, a partition in said barrel forming a lead magazine, said partition having an axial opening in line with the lead passage of the tip, a plunger operable in said axial opening of said partition, said partition having a feed slot and means for

feeding a succession of leads from the magazine through said feed slot of the partition and to said tip.

41. A mechanical pencil having a barrel formed with a tip, a rotatable partition in said barrel providing a lead magazine, said partition having an axial opening in line with the lead passage of the tip, a rod operating in said axial opening of the partition, said partition having a radial feed slot, means for rotating said partition about its axis and means for feeding a lead through the slot of the partition and to the tip.

42. A mechanical pencil having a barrel formed with a tip and provided with a longitudinally slotted charging tube and with an axially apertured disc forming a transverse partition for the intermediate portion of the barrel, said charging tube terminating at its upper end in an axially apertured cup-shaped member whereby to form a lead magazine between the disc and the cup-shaped member, a screw and plunger rotatably mounted within the tube and passing through the axial openings in said disc and cup-shaped member, said disc and cup-shaped member having feed slots therein, a feeding tube mounted in said charging tube and communicating with said tip and forming a guide for the plunger to feed the lead to the tip, and means in said magazine for feeding a succession of leads from the magazine through the slot in the partition and to the feeding tube.

In witness whereof, I hereunto subscribe my name to this specification.

HERBERT W. JOHNSON.

CERTIFICATE OF CORRECTION.

Patent No. 1,705,865.

Granted March 19, 1929, to

HERBERT W. JOHNSON.

It is hereby certified that error appears in the printed specification of the above numbered patent requiring correction as follows: Page 5, line 74, claim 8, after the word "lead" insert the words and comma "in said guide to said tip and for feeding a lead,"; and that the said Letters Patent should be read with this correction therein that the same may conform to the record of the case in the Patent Office.

Signed and sealed this 18th day of June, A. D. 1929.

(Seal)

M. J. Moore,
Acting Commissioner of Patents.

through the tip and through the magazine.

37. A pencil having a barrel provided with a tip and a magazine for extra leads, a rotatable feed screw, a rod and means for causing said rod to rotate with said screw or to move longitudinally thereof whereby to feed leads from the magazine toward the tip.

38. A mechanical pencil having a barrel provided with tip and a magazine for extra leads, a feed screw, a lead feed rod actuated by said screw and having a crook, a slotted charging tube surrounding said screw, and a slotted guide-sleeve surrounding said tube, said screw tube and sleeve having frictional driving faces and having portions to engage said crook for causing said feed rod to rotate with said screw or to travel longitudinally thereof to feed a lead from said magazine to said tip.

39. A mechanical pencil having a barrel provided with a tip, a partition extending across said barrel intermediate its ends and forming a lead magazine on that side of the partition removed from the tip, a feed rod adapted to move axially through said partition to feed leads to and through the tip, said partition having an eccentric feed slot therethrough, and means for feeding a succession of leads from the magazine through said eccentric slot.

40. A mechanical pencil having a barrel formed with a tip, a partition in said barrel forming a lead magazine, said partition having an axial opening in line with the lead passage of the tip, a plunger operable in said axial opening of said partition, said partition having a feed slot and means for

feeding a succession of leads from the magazine through said feed slot of the partition and to said tip.

41. A mechanical pencil having a barrel formed with a tip, a rotatable partition in said barrel providing a lead magazine, said partition having an axial opening in line with the lead passage of the tip, a rod operating in said axial opening of the partition, said partition having a radial feed slot, means for rotating said partition about its axis and means for feeding a lead through the slot of the partition and to the tip.

42. A mechanical pencil having a barrel formed with a tip and provided with a longitudinally slotted charging tube and with an axially apertured disc forming a transverse partition for the intermediate portion of the barrel, said charging tube terminating at its upper end in an axially apertured cup-shaped member whereby to form a lead magazine between the disc and the cup-shaped member, a screw and plunger rotatably mounted within the tube and passing through the axial openings in said disc and cup-shaped member, said disc and cup-shaped member having feed slots therein, a feeding tube mounted in said charging tube and communicating with said tip and forming a guide for the plunger to feed the lead to the tip, and means in said magazine for feeding a succession of leads from the magazine through the slot in the partition and to the feeding tube.

In witness whereof, I hereunto subscribe my name to this specification.
